RANGE TARGET

Frank H. Schwerin, Bellevue, Pa., assignor to
 The Duff-Norton Manufacturing Company,
 Pittsburgh, Pa., a corporation of Pennsylvania

Application January 22, 1935, Serial No. 2,902

8 Claims. (Cl. 273—105.6)

This invention relates to improvements in target apparatus for shooting ranges. The invention relates more particularly to apparatus for changing the positions of the targets and to control means for causing the targets to remain in their various positions for predetermined periods of time and then change their positions in synchronism.

In revolver and rifle marksmanship competition a contestant is allowed a given length of time in which to fire his shots, and the expiration of the allotted time is ordinarily determined by a referee with a stop-watch. This method of timing firing periods is often unsatisfactory. Disputes arise as to whether the referee terminated the firing period in exact accordance with the stop-watch, or whether the last shot of a certain contestant was actually fired after the elapsed time. Disputes arise also over differences in stop-watches.

It is an object of this invention to eliminate the human element from the determination of the allotted time in revolver and rifle marksmanship competition. The invention attains this object by automatically rotating the targets out of shooting position upon termination of the allotted firing period. This removal of the targets eliminates the possibility of one contestant taking an unfair advantage of others by firing one last shot after the allotted period. The timing is mechanical. Every contestant knows that he has a fair and equal chance, and disputes are eliminated.

Another object of the invention is to provide a target-carrying frame which can be rotated on its supporting structure to turn the target to face the shooter or turn it edgewise toward the shooter. Another object is to provide a target-carrying frame of the type indicated with means for moving the frame from a position in the line of fire to a protected position for inspecting and replacing targets in addition to the rotational movement of the target. On outdoor ranges the targets are ordinarily lowered into a pit for inspection and replacement, while indoor targets are usually moved horizontally into a position where the targets can be replaced with safety. This invention can be embodied in either the indoor or outdoor type of target apparatus.

Other objects of the invention are to combine a target-carrying frame with simple and effective mechanism for rotating the frame to turn the target alternately to face the shooter and into a position edgewise toward the shooter, and to provide control means for causing the mechanism to

operate at predetermined times. One part of the control means comprises a novel timer which is particularly simple and inexpensive to manufacture and which can be accurately set for different firing periods quickly and conveniently. 5

Other objects of the invention are to provide improved mechanism for raising and lowering targets on a range having a target pit, and to control the movements of a number of targets so that they move into or out of shooting position 10 simultaneously.

Other objects, features and advantages of the invention will appear or be pointed out as the specification proceeds.

In the accompanying drawings, forming part 15 hereof:

Fig. 1 is a front elevation of three target devices located in a pit and with their target-carrying frames in raised position so that the targets are in the line of fire; 20

Fig. 2 is a plan view of the target devices shown in Fig. 1;

Fig. 3 is an enlarged sectional view along the line 3—3 of Fig. 1, but with the target-carrying frame shown in lowered position and the wiring 25 diagram of the motor control circuit shown diagrammatically;

Fig. 4 is an enlarged fragmentary view showing a part of the mechanism for edging the targets; 30

Fig. 5 is a wiring diagram including the motor and control switch shown in Fig. 4;

Fig. 6 is an enlarged fragmentary view, partly in section along the line 6—6 of Fig. 4, showing the cam means by which the target-carrying 35 frames are turned;

Fig. 7 is an enlarged sectional view taken on the line 7—7 of Fig. 1;

Fig. 8 is a side elevation of a modified form of the invention designed for indoor use; 40

Fig. 9 is a front view of the modified form of the invention shown in Fig. 8;

Fig. 10 is a top view of a device for timing the operation of the targets, the cover of the timer being removed; and 45

Fig. 11 is a sectional view of the timer shown in Fig. 10, with the cover in closed position.

Fig. 1 shows three target devices 10, 11 and 12 located in a pit at the end of a shooting range. Each of these target devices includes a fixed 50 frame structure 14 which rests on the bottom 15 of the pit. The top of the fixed frame structure is lower than the edge of the pit. The pit edge or ground level is indicated in Fig. 1 by the reference character 16.

A target-carrying frame 18 is connected to the upper end of a shaft 19 which is carried by a movable supporting frame 20 which slides vertically in the fixed frame. A target 21 is carried by the frame 18. Weights 22 are connected to the ends of cords 23 which pass over pulleys 24 at the upper end of the fixed frame, and are fastened to the movable frame 20 to counter-balance the weight of the movable frame and target-carrying frame.

The movable frame 20 is raised and lowered by a chain 26, which passes over a wheel 27 (Fig. 3) near the top of the fixed frame 14 and over a sprocket 28 near the bottom of the fixed frame. The chain 26 is fastened to the movable frame 20 by a connection 30. The wheel 27 is supported from the fixed frame 14 for rotation about a fixed axis.

The sprocket 28 is secured to a drive shaft 32 which turns in bearings 33 (Fig. 2) on the fixed frame 14. The drive shaft 32 extends beyond the fixed frame and is connected with the corresponding shaft of the next target device by a coupling 35. The drive shafts of all of the target devices in the pit are connected in this manner so that they turn as a unit.

A sprocket 36 is secured to the drive shaft of the target device 11. The sprocket 36 is connected with a driving sprocket 37 by a chain 38. The driving sprocket receives its power from an electric motor 39 through a worm-gear speed reducer 40. Simultaneous rising and lowering of the targets is assured by the use of the common motor 39 for moving all of the targets. Although an electric motor is a convenient source of power, other operating means for rotating the drive shafts 32 can be employed, such as a manually-operated crank connected to the sprocket 37.

Fig. 1 shows the targets 21 in raised position and facing the shooters. After the targets have been fired at, the motor 39 is operated to lower the supporting frames 20 and target-carrying frames 18 into the pit so that the targets are below the top edge of the pit and out of the line of fire. In this lowered position the targets can be inspected and replaced with perfect safety. When targets are to be raised again into shooting position, the motor 39 is rotated in the reverse direction and the frames and targets are moved into their raised positions shown in Fig. 1.

A limit and reversing switch 42 on the fixed frame of the target device 11 has an operating arm 43 in position to be moved downward by the supporting frame 20 as it reaches its lower limit of movement. As the frame 20 reaches its upper limit of movement, it displaces a lever 44 which is connected to the switch operating arm 43 by a link 45, the exact length of which can be adjusted by a turnbuckle 46.

The switch 42 and its connections to the motor 39 are shown diagrammatically in Fig. 3. The switch 42 is a double-throw switch and closes the circuit from a power line 47 to one side or the other of a reversing switch 48. The reversing switch is normally held in the position shown in Fig. 3 by a spring 48a. In this position the switch 48 connects the lower contact of the switch 42 with the motor 39 in a manner to cause rotation of the motor in a direction to raise the targets. A solenoid 48b is connected with the switch 48, and this solenoid, when energized, shifts the reversing switch and holds it in position to supply power to the motor from the upper contact of switch 42 and in a manner to cause rotation of

the motor in a direction to lower the targets. The supply of power to the solenoid is controlled by manually-operated three-point switches 49 connected in series with the solenoid. One of the switches 49 can be located in the pit and the other in the judges' stand so that the raising and lowering of the targets can be controlled from either location.

The construction of the fixed frame 14 is shown in detail in Figs. 1, 3 and 7. Each side of the frame is made from two vertically extending angles 50 which are rigidly fastened to the plates 51. The sides of the fixed frame are connected by horizontal angles 53 which are bolted to the upper and lower ends of the vertical angles 50. A vertical guide 54, best shown in Figs. 1 and 7, is fastened to the tie plates 51 on each side of the fixed frame. The movable frame 20 fits loosely between the guides 54 and has extensions 55 which cooperate with the guides 54 to prevent forward and aft displacement of the movable frame.

When the target-carrying frames are in their raised positions, they can be rotated to turn them edgewise toward the shooters. The frames 18 are shown in such positions by dot-and-dash lines in Fig. 2. The mechanism for turning the targets is best shown in Figs. 4 and 6. A casting 57 is rigidly fastened to vertical angles 53 of the movable supporting frame 20 and forms a part of the supporting frame. A thrust collar 60 bears against the upper portion 61 of the casting 57 and carries the weight of the frame 18. The shaft 19 extends through bearings in the upper portion 61 and lower portion 62 of the casting 57. A collar 63 on the shaft 19 just below the upper portion of the casting 57 prevents upward movement of the shaft 19 and its connected frame 18.

A sleeve 64 surrounds the lower part of the shaft 19. There is a cam slot 65 (Fig. 6) in the sleeve 64, and a pin 66 extends from the shaft 19 into the cam slot and serves as a cam follower. The sleeve 64 has a flange 68 (Fig. 4) at its lower end, and this flange straddles guide rods 69 which extend between the upper and lower portions of the casting 57 and prevent the flange and sleeve from turning. An electric motor 70 is supported from the casting 57 by hangers 71. A screw shaft 72 extends from the motor 70 shaft in alignment with the shaft 19.

A nut 74 is fastened to straps 75 and these straps are secured to the sleeve 64 at their upper ends. The screw shaft 72 threads through the nut 74 so that rotation of the motor moves the nut 74 up or down, depending on the direction of rotation, and raises or lowers the sleeve 64. This vertical movement of the sleeve 64 causes the cam slot 65 to move the cam follower or pin 66 so as to rotate the shaft 19.

The angular extent of the cam slot 65 about the axis of the shaft 19 is substantially 90 degrees so that the shaft is turned through a right angle when the sleeve moves the full length of the cam slot. The ends of the cam slot are substantially vertical, however, so that the first and last parts of the movement of the cam slot produce no rotation of the shaft 19. This feature of the cam slot allows considerable latitude in the position at which the movement of the sleeve 65 must stop. It is important for the target to face the shooter with the plane of the target at right angles to the line of fire, in one position, and to be disposed at right angles to this position when turned edgewise to the shooter.

The vertical end portions of the cam slot 65 allow considerable variation in the position in which the motor and sleeve 64 can stop without affecting the final positions of the target, and also serve as locks to hold the targets in position against severe wind conditions or other external forces, and permit a low starting torque motor to attain speed before taking the load.

10 A switch 77 attached to one of the angles 58
has an arm 78 extending through a bracket 79.
The bracket 79 moves up and down as a unit
with the sleeve 64 and has screws 80 which serve
as abutments for moving the arm 78 to operate
the switch 77 when the sleeve 64 approaches
15 either its upper or lower limit of movement.
The screws 80 thread through the bracket 79 and
can be adjusted to operate the switch 77 earlier
or later to obtain the desired movement of the
sleeve 64.

Fig. 5 shows a wiring diagram for the switch 77. This switch is of the double-throw type and supplies power selectively to opposite sides of a reversing switch 81, which is normally closed in one direction by a spring 81^a but is thrown and held closed in the opposite direction by a solenoid 82 when this solenoid is energized. The supply of power to the solenoid 82 is controlled by a timer or timing device 83, which will be described fully in the explanation of Figs. 10 and 11. The diagrammatic illustration of the timer in Fig. 5 shows a disk 85, which rotates at a substantially uniform speed and carries with it a projection 86 and an arm 87. The end of this arm extends beyond the end of the disk for substantially the same distance as the projection 86. A relatively fixed contact 88 is located close to the periphery of the disk 85 in position to be brushed by the projection 86 and arm 87 as they rotate with the disk. When either the projection 86 or the arm 87 is touching the contact 88, a circuit is closed to the solenoid 82 and the solenoid is energized. A manually operated momentary-contact switch 89 can be closed to energize the solenoid 82 at any time. The supply of power to the timer is controlled by a switch 90.

The switch 77 is similar to the switch 42 and has its movable contact or blade portion connected with the power line. The switch 77 has fixed contacts 91 and 92, which are connected with contacts 93 and 94, respectively, of the reversing switch 81. When the sleeve 64 approaches the downward limit of its travel, the arm 78 is moved downward and the blade portion of the switch is moved into contact with the fixed contact 92, as shown in Fig. 4. The switch 77 remains in this position until the sleeve 64 approaches the upper limit of its travel and the arm 78 is lifted to move the blade portion of the switch away from the fixed contact 92 and into contact with the upper fixed contact 91.

When the switch 77 is closed against its lower contact 92 and the switch 81 is in the position shown in Fig. 5, current flows from the power line through the switch 77 to the contact 94, and through a conductor 95 of the switch 81 to a contact 96, which is connected with the armature circuit of the motor 70. The field of the motor 70 is connected in series with the armature through a conductor 97 of the switch 81.

70 When the switch 77 is closed against the upper contact 91, the circuit to the motor is not complete beyond the contact 93 unless the solenoid 82 is energized to shift a conductor 98 into position to complete the circuit to the motor armature. Current supplied through the con-

ductor 98 flows through the armature of the motor 70 in a reverse direction from that supplied through the conductor 95, and thus reverses the direction of rotation of the motor, the field current remaining unchanged.

A conductor 98^a of the switch 81 connects the armature and field of the motor 70 when the solenoid 82 is energized. The conductors 95 and 97 are moved away from their switch contacts by the solenoid 82. A resistance coil 99 in series with the motor 70 limits the motor speed and obtains smoother operation of the targets. The resistance 99 is variable because different amounts of resistance are desirable, depending upon the number of target motors controlled by the timer.

All of the target devices are connected in parallel with the timer by conductors 100, as shown in Fig. 1. Since the timer is portable it is preferably connected with the conductors 100 through plug and receptacle connections 100a. The conductors 100 connect with a fixed receptacle 100b (Fig. 3) at the top of the fixed frame structure 14. A plug 100c is carried by the movable supporting frame 20 and has contacts which cooperate with complementary contacts in the receptacle to complete the circuit between the conductors 100 and the electrical apparatus in the movable supporting frame 20. Since the motor in the movable supporting frame is operated only when the frame is in its raised position, there is no necessity for connecting this motor with the conductors 100 when the movable frame is in a lowered position. This receptacle and plug connection avoids trailing wires leading to the movable supporting frame, and protects the target-rotating mechanism from accidental operation at times when it is impossible for the target to rotate.

Figs. 8 and 9 show a modified form of the invention for indoor use. The target-carrying frame 18 rests on the collar 60 on a supporting frame 101, which houses target-rotating mechanism similar to that shown in Figs. 4-6. The frame 101 has a base with wheels 102 running on a track 103. An armor plate 104 protects the frame 101 from low bullets. This plate slopes forward to allow space for the target-carrying frame 18 to swing into its edgewise position and to deflect the bullets downward.

The target apparatus shown in Figs. 8 and 9 is pulled forward along the track 103 to the shooter when a target is to be replaced. An endless cable can be employed to move the target apparatus along the track 103. Since the mechanism for edging the target is operated only when the apparatus is at the far end of the track 103, it is not necessary to have any power connections to the apparatus except when it is at that end of the track. Contacts in a socket 106 are connected with the conductors 100 leading to the timer. Contacts 109 and 110 carried by the frame 101 touch the contacts in the socket 106 when the target apparatus is at the far end of the track. This feature of the invention makes it unnecessary to have a trolley for supplying power to the target-rotating motor in the frame 101 and has the further advantage that the apparatus can not be operated unless it is the full distance from the shooter.

Figs. 10 and 11 show the construction of the timer 83. A case 115 has a cover 116 connected to it by a hinge 117. The cover is removed in Fig. 10 to expose the means for setting the timer. A panel 118 covers the motor chamber of the 75

case 115, and a glass panel 119 covers the switch chamber.

A uniform-speed electric motor 121 drives a pinion gear 122 through bevel gearing 123. The pinion gear 122 drives a large gear 125 which turns freely on a shaft 126 extending from the motor frame. The hub of the gear 125 is tapered and extends into a tapered recess in a collar 128 to form a cone clutch 129. The collar 128 is secured to a shaft 130 and to the hub of the disk 85. The shaft 130 extends upward above the glass panel 119 and has a knob 131 at its upper end. The knob is of insulating material and is secured to the shaft 130 by a pin 132. The ends of the pin are covered by an insulating sleeve 133 so that an attendant can not receive a shock from the pin.

The disk 85 is driven by the motor 121 through the clutch 129, but the friction of this clutch is light enough to permit the disk to be rotated by the knob 131 independently of the motor.

The arm 87 has a hub 135 which turns freely on the shaft 130. A knob 138, of insulating material, is secured to the hub 135 and is used to turn the arm 87 with respect to the disk 85. The disk has a circle of indexing holes 136, and the arm 87 has a protuberance 137 which extends into any of these indexing holes with which it is in register. When the protuberance 137 is in any of the indexing holes 136, the arm 87 turns as a unit with the disk 85. When the setting of the timer is to be changed, the setting knob 138 is lifted slightly and turned to engage the desired indexing hole with pin 137.

The contact 88 is carried by a bracket 140 which is fastened to the panel 118. The contact 88 has no angular movement about the axis of the disk 85, but the bracket yields to permit a slight radial movement of the contact 88 when the projection 86 and arm 87 brush against it.

When the projection 86 breaks its contact with the contact 88, the firing period begins. When the end of the arm 87 touches the contact 88 the firing period is terminated. The timer shown in the drawings rotates the disk 85 once in six minutes. A firing period of one minute is obtained, therefore, when the disk must move ten degrees, after the projection 86 leaves contact 88, to bring the arm 87 against the contact 88. Legends at the indexing holes indicate the firing period obtained with the arm 87 set at each indexing hole.

The length of the contact 88 which bears against the projection 86 and arm 87 determines the length of the period during which the targets remain edgewise toward the shooters. The contact 88 shown in the drawings is designed to give an edgewise period of five seconds. The projection 86 and the arm 87 are a part of the electric circuit in the timer illustrated, but it will be understood that the contact 88 may be replaced by a momentary contact switch and the projection 86 and arm 87 employed as cam means for closing such a switch in a circuit of which they are not a part.

The operation of the invention will be reviewed briefly. Referring to Figs. 1 and 3, the cycle of operation of the targets starts with the target-carrying frames 18 in their lowered positions below the top edge 16 of the pit. With the parts in the positions shown in Fig. 3, power is supplied to the motor 39 through the lower contact of the switch 42, and the motor rotates the shaft 32 in a direction to raise all of the targets into shooting position, as shown in Fig. 1. This ris-

ing of the targets from the pit is a signal to the shooters to take their places on the line and to load.

The timer 83 (Fig. 5) is then started, the disk 85 having been set so that the projection 86 will touch the contact 88 almost immediately after the starting of the timer. As soon as the projection touches the contact 88 the targets turn into the positions shown in dot-and-dash lines in Fig. 2 edgewise toward the shooters, and dwell in this position for five seconds.

At the end of five seconds the projection 86 moves away from the contact 88 and the targets turn back into the shooting position shown in Fig. 1. This reappearance of the targets is the signal to "fire".

The targets remain in shooting position until the arm 87 of the timer moves into contact with the contact 88. When the arm touches this contact, the target-turning mechanism rotates the targets into their edgewise positions and terminates the firing period. The targets remain edgewise to the shooters for a period of five seconds while the arm 87 brushes across the contact 88, and then return to shooting position so that they can be lowered into the pit for inspection and replacement. The motor 39 (Figs. 1 and 3) is operated to lower the targets by operating either of the switches 49 to close the circuit to the solenoid 48^b so that the switch 48 is moved into position to connect the motor with the upper contact of the switch 42. Since the switch 42 is closed against its upper contact when the targets are raised, this movement of the switch 48 connects the motor with the power line and causes rotation of the motor in a direction to lower the targets.

The preferred embodiments of the invention have been described, but other embodiments can be made within the scope of the claims, and some features of the invention can be used alone.

I claim:

1. Target apparatus comprising a target-carrying frame, a vertical shaft supporting the frame and extending downward from the frame, a bearing in which the shaft rotates, a motor, an operating member operatively connected with the motor and adapted to be raised and lowered by the motor, and cam means between the shaft and said operating member for causing the shaft to rotate and turn the target-carrying frame in response to vertical movements of said operating member.

2. Apparatus of the class described comprising a target-carrying frame, supporting means for said frame, a shaft connecting the frame with said supporting means for rotary movement with respect to said supporting means, a fixed structure to which said supporting means is movably connected for vertical movement with respect to the fixed structure to raise the target frame into the line of fire or lower it into a pit for inspection and replacement of targets, and mechanism carried by the supporting means and movable with the supporting means as a unit, said mechanism including an electric motor, a motion transmitting connection which is moved vertically by the rotary movement of the motor, and cam means between the shaft and said connection for causing a partial rotation of the shaft in response to vertical movement of said motion transmitting connection.

3. In a target range for marksmanship competition, stationary supporting means located in a pit and holding a plurality of target frames

which are movable with respect to the supporting means to raise said target frames above the pit or lower them into the pit for inspection and renewal of targets, and mechanism limiting the exposure of each target to the contestants to an exactly equal time, said mechanism including means for causing each of the target frames to turn about an upwardly extending axis passing through that frame to bring a target carried by the frame into a position edgewise toward the shooter, and connections between the turning means of the separate target frames for causing all of said turning means to operate simultaneously so that the targets of the respective contestants face or turn away from them at the same instant.

4. Target apparatus for marksmanship competitions in which each contestant must fire his shots within an allotted period of time, said apparatus including in combination a supporting structure which remains stationary at one end of the range during the firing period, a target-carrying frame supported by said structure and movable up and down with respect to said structure to raise said frame into the line of fire or lower it into a protected position, said frame being also rotatable with respect to the supporting structure about an axis transverse of the line of fire so that a target on the frame can be moved into a position facing the contestant or edgewise toward the contestant, motor means for causing the frame to turn quickly between its positions facing and edgewise toward the contestant, and automatic mechanical means insuring to the contestant the exact firing period allotted to him, said automatic mechanism including a timer a switch operated by the timer for operating the motor means to turn the target to face the contestant and after a given lapse of time to operate the motor means to turn the target edgewise toward the contestant.

5. Target apparatus for marksmanship competitions in which each contestant must fire his shots within an allotted period of time, said apparatus including in combination a supporting structure which remains stationary at one end of the range during the firing period, a target-carrying frame supported by said structure for rotation about an axis transverse of the line of fire so that a target on the frame can be moved into a position facing the contestant or edgewise toward the contestant, means for causing the frame to turn quickly, said means comprising an electric motor, a vertically extending screw driven by the motor, a nut on said screw constructed and arranged to be raised and lowered by the rotation of the screw in one direction or the other, a cam and follower, one of which is connected with the nut and the other with the target-carrying frame

to rotate said frame in response to vertical movement of the nut.

6. Target apparatus comprising a stationary supporting structure for location in a pit, a target-carrying frame movable on the supporting structure to raise the frame above the pit into the line of fire or lower the frame into the pit for the inspection and replacement of targets, and mechanism for turning the target-carrying frame with respect to the supporting structure to bring a target into position facing the line of fire or edgewise of the line of fire, said mechanism including electric motor means on the target-carrying frame and movable up and down with said frame as the latter is raised and lowered, and means for supplying power to said motor means when the frame is in an elevated position.

7. Target apparatus comprising a stationary supporting structure for location in a pit, a target-carrying frame movable on the supporting structure to raise the frame above the pit into the line of fire or lower the frame into the pit for the inspection and replacement of targets, and mechanism for turning the target-carrying frame with respect to the supporting structure to bring a target into position facing the line of fire or edgewise of the line of fire, said mechanism comprising an electric motor, a vertically extending screw driven by the motor, a nut on said screw constructed and arranged to be raised and lowered by the rotation of the screw in one direction or the other, a cam and follower, one of which is connected with the nut and the other with the target-carrying frame to rotate said frame in response to vertical movement of the nut.

8. In or for a target range, fixed supporting means for location in a pit, a plurality of target-carrying frames movable up and down with respect to said supporting means for raising targets above the pit and into the line of fire or lowering them into the pit for inspection and renewal, at least a part of each of said frames being rotatable with respect to the supporting means about an upwardly extending axis to turn the target edgewise toward a shooter, sprocket chains connected with the respective frames, wheels over which the chains run, said wheels being carried by the supporting means and including driving sprockets for the respective chains, shafting connecting the sprockets so that all of them operate simultaneously to raise or lower the target-carrying frames, and mechanism connected with said frames for rotating them simultaneously about their upwardly extending axes to edge the targets or turn them to face the line of fire.

FRANK H. SCHWERIN.
